UNITED STATES PATENT OFFICE.

EDWARD C. BACHEFIELD, OF INDIANAPOLIS, INDIANA.

RAILWAY-BED.

1,256,095.

Specification of Letters Patent. Patented Feb. 12, 1918.

Application filed April 16, 1917. Serial No. 162,242.

To all whom it may concern:

Be it known that I, EDWARD C. BACHEFIELD, a citizen of the United States, residing at Indianapolis, in the county of Marion 5 and State of Indiana, have invented certain new and useful Improvements in Railway-Beds, of which the following is a specification, reference being had therein to the accompanying drawing.

10 This invention relates to improvements in railway-beds.

The object of the invention is to provide a substantially solid or nonyielding bed upon which the cross ties and superimposed rails 15 shall be laid, with the view of practically eliminating the common present defect in railway-beds of vibration or yieldability under the traveling weight of trains.

In railway construction up to this time 20 the railway-beds, usually constructed of embankments of earth, sometimes intermixed with stone, and overcapped with gravel, cinders or broken rock are so far yieldable under the influence of the weight

25 of trains as to cause an unobserved though potent wave-like action of the rails as the trains proceed over them. That is to say, the bed and the superimposed rail structure settle somewhat from point to point as the 30 train proceeds. This settling is irregular, being greater at some places than at others, so that there is an unobserved yet actual wave-like motion of the rails. This results in producing vibrations, principally up and 35 down. As the causes of these vibrations are irregular and as their extent is inconstant, so they become and are unrhythmic. The effect of this is a gradual but continuous depreciation of both rolling stock

40 and road-bed, including in the latter term the rails and ties and fastening attachments for the rails.

The object of my invention is to overcome 45 all this. This object I carry into effect by a construction of road-bed upon which the ties and rails are superimposed that will neither itself yield or vibrate nor permit the ties and rails to do so.

In carrying out my invention I construct 50 upon the graded road-bed proper a base of such solidity and strength and of such broad contact with the bed proper, as distinguished from a succession of cross ties resting at intervals on the bed, each tie affording but a small surface, and which is easily

depressed, as will not be subject to this yieldability and these wave-like undulations which cause, in the common existing road-beds, the vibrations above alluded to. I eliminate vibration and substitute solidity. 60

In further carrying out my invention I secure the ties to this base in an immovable manner so that no vibration is permitted as between the ties and the base.

Thus, my invention comprehends a new 65 system of railway-bed in which solidity and non-yieldability are the characteristics which distinguish it in principle from the common road-beds with their universal defect of yieldability, productive of vibrations 70 in the rolling stock.

In the accompanying drawings, Figure 1 is a cross section of my improved road-bed showing one type of rail tie mounted thereon; Fig. 2 is a perspective view of a portion 75 or section of the base which enters into the road-bed; and Fig. 3 is an inverted perspective view of one end of such a cross tie as may be used with this bed.

At 1 is indicated a railway-bed proper, 80 being the bank of earth usually employed and graded to suit the particular location. This bed proper may be wholly of earth or a combination of earth and stone or rocks, as may be incident to the locality. The 85 change I make from the old to the new in this respect is in forming the upper surface of this bed 1 of convex contour, as indicated at 2. The object in this is to aid in preventing any side shifting of the base which is 90 to be constructed upon this bed, as the base is concave to fit the convex line of the bed. In this way there is in effect a lateral interlocking of the base to the bed. Of course, this line of contact may be other than convex so long as the interlocking feature is 95 preserved, but I prefer the convex and concave meeting surfaces.

The base is indicated at 3 and consists of a solid body built upon the bed and extending lengthwise thereon indefinitely according to the extent of the particular road under construction. This base is preferably composed of a mixture of cement with sand and gravel or broken rock in such proportions as will make a firm and solid body. Usually the proportion of one part of cement to six parts of the remainder of the material combined will be effective. This base, though in effect continuous, is in fact 105 110

constructed in sections, say of thirty or more feet in length, a fine divisional line being formed by any of the usual modes employed in cement work to prevent cracking from the effects of cold.

The upper face of the base is fashioned into a sort of basin, as indicated at 4, so that it will readily hold a super-base of similar material, but of a different consistency. This super-base will preferably be of cream-like consistency so that it may be readily manipulated in a manner to effect a perfect level or to conform to an adopted grade. This super-base will be made of cement and sand, with the addition of gravel or small broken rock.

It is upon the latter that the cross ties with their superimposed rails will be placed. While I have shown a special type of cross tie, which is being made the subject of a separate patent application filed of even date herewith, Ser. No. 162,243, it is to be understood that any kind of cross tie found suitable for the purpose, even the common wooden tie, may be used. The tie shown comprises a cast metal block 5 formed with a seat 6 for the base of the rail. A clamp 7 having a horn 8 is secured to the block by a bolt 9. The clamp fits against the web of the rail and the horn 8 fits between one side of the rail base and the dovetailed wall 10 of the rail seat. The effect is to firmly lock and hold the rail to the tie block against all lateral movement or tipping, yet allowing of the expansion and contraction, particularly longitudinally, of the rail.

Each pair of blocks is connected by a cross tie proper 11, preferably made in tubular form and united with the tie blocks in any convenient manner, as by having the blocks cast over and around the ends of the tie rod.

The blocks are preferably armed with projections or prongs 12 to enter down into the super-base while in a plastic or unset state.

At either side and between the tie blocks gravel, broken stone or other suitable ballast is piled upon the super-base, as an additional anchoring means for the ties. And so also at either side of the base 3, there will usually be embanked ballast or other material, as indicated at 13, to shed the water from the base and to further insure its interlocking with the bed.

It will be understood that suitable forms will be constructed for laying the material to compose the base, as is usual in cement work. It will further be understood that the upper face of the base will be graded longitudinally and leveled laterally according to the prevailing grade and to the curves in the road-bed. These levelings are the work of the engineer.

It will further be particularly understood

that there shall be such leveling of the rails, that each succeeding rail shall be at the proper height with respect to the adjoining rails, their surfaces to be in one continuous plane whether horizontal or inclined; and also that the rails at one side shall be at such altitude with respect to the rails on the other side, whether in the same horizontal plane or in different horizontal planes, according to the grade and curves. These positionings of the ties and in turn of the rails, when the latter are later applied are a feature of prime importance. The feasibility of properly positioning the cross ties or tie blocks is a direct result from the use of the plastic super-base, permitting of the nicest application of the engineering art in positioning these supports for the rails. This feasibility is one of the results of my invention, followed by the fact that one set of ties or tie blocks are permanently set by reason of the solidifying of the super-base upon the solid base.

Thus it will be observed that I first build a solid and unyielding base, on this a temporarily yieldable super-base upon which the ties or tie blocks are leveled, graded or positioned, followed by the "setting" of the super-base and fixity of the tie or tie block.

From this structure I have eliminated, to all practical purposes, the element of vibration or yieldability and have provided instead solidity, fixity and permanence.

While I have shown and described one embodiment of my invention, it will be understood that the same has been chosen for the purposes of illustration, and that I do not desire to be limited to the details of construction shown and described, for obvious modifications will occur to a person skilled in the art.

Having thus fully described my invention, what I claim as new and desire to secure by Letters Patent, is:—

1. In a railway-bed, the combination, of a bed proper, a non-yielding base on the bed, a super-base located on the base and having the quality of being temporarily plastic and later becoming solid, and rail supports in the nature of ties set to position in the super-base and solidly supported by the solidification thereof.

2. In a railway-bed, the combination, of a bed proper, a non-yielding base on the bed and interlocked therewith, a super-base located on the base and held by the latter against lateral displacement, and rail supports in the nature of ties set to position in said base and interlocked therewith, the super-base having the quality of being temporarily plastic and later becoming solid.

3. In a railway-bed, the combination, with a bed proper, a base constructed thereon of cement composition and adapted to form an unyielding body, a super-base con-

structed of plastic material on the base, and rail supports in the nature of ties embedded in said base.

4. In a railway-bed, the combination, of a bed proper, a non-yielding base on the bed, a super-base located on the base and having the quality of being temporarily plastic and later becoming solid.

5. In a railway-bed, a bed proper, a base 10 constructed of a cement composition upon and interlocked with the bed, and having its upper surface elevated at the sides, and a super-base constructed of a cement composition and placed upon the upper surface 15 of the base.

6. In a railway bed, the combination, with a bed proper, and a non-yielding base on the bed, forming a solid body to bear over

an extensive area of the bed and to support over an extensive area a superposed rail structure, the contour of the bottom of the base and the top of the road bed being such as to assist in preventing side shifting of the base, of a super-base located on the base and constructed of temporarily plastic material, 25 and rail supports set to position in the super-base.

7. In a railway-bed, a base constructed to overlie the bed proper laterally and longitudinally over an extended area, and a super-base constructed of material placed upon the upper surface of the base in a plastic state and adapted to later solidify.

In testimony whereof, I affix my signature.

EDWARD C. BACHFIELD.
